D. H. BROWDER

PIPE REAMER

Filed Feb. 11, 1922

Mr. May. Howell.

BY *Victor J. Evans*
ATTORNEY

D. H. Browder

INVENTOR

UNITED STATES PATENT OFFICE.

DAVID H. BROWDER, OF LAWRENCEVILLE, VIRGINIA.

PIPE REAMER.

Application filed February 11, 1922. Serial No. 535,876.

To all whom it may concern:

Be it known that I, DAVID H. BROWDER, a citizen of the United States, residing at Lawrenceville, in the county of Brunswick 5 and State of Virginia, have invented new and useful Improvements in Pipe Reamers, of which the following is a specification.

In injectors for locomotives, etc., it is absolutely necessary that a fluid tight joint be 10 provided between the injector and the pipes connected thereto. Therefore the joints between the bosses or nipples of the injector and the pipes therefor are ground, the bosses or nipples having their ends flared in one direction and the pipes having their ends flared in an opposite direction, while unions 15 are provided for connecting the pipes and nipples. Because of the necessary accurate contacting engagement of the pipe with the 20 boss or nipple care must be taken in grinding or facing the joints therebetween, and in the majority of instances it is necessary to remove the injector in facing the bosses or nipples thereof.

The primary object of the present invention is to produce a tool for facing the joints between an injector and the pipes connected therewith, which can be readily secured on the injector without the removal thereof and 25 which likewise can be readily secured on the pipes to be connected to the injector, and wherein the joints of these members can be faced in an easy, accurate and expeditious manner without unnecessary physical exertion.

It is a further object to produce a facing tool for joints of injectors and pipes connected thereto, which shall include means 30 for clamping the same on the injector or on the pipe, a frame being secured on said clamping means and having journaled thereto a shaft to which the cutter head is connected, a removable handle being provided for operating the shaft, while arranged on the frame, and in contact with the cutter head there is a feed element adjustable on the frame to direct the head to its work.

A still further object is to produce a facing tool for this purpose characteristic of simplicity in construction, lightness in 40 weight and ease and accuracy in operation.

The foregoing, and other objects which 45 will appear as the nature of the invention is better understood, may be accomplished by a construction, combination and operative

association of parts such as is disclosed by the drawings which accompany and which form part of this specification.

In the drawing:

Figure 1 is an elevation illustrating the application of the improvement.

Figure 2 is a similar view taken at right angles to the showing in Figure 1, the handle for the shaft being removed.

Figure 3 is a sectional view approximately on the line 3—3 of Figure 2.

Figure 4 is a bottom plan view of the improvement.

Figure 5 is a side elevation of one of the 70 cutter heads.

Figure 6 is a sectional view of a joint between the boss or nipple of an injector and the pipe therefor.

Referring now to the drawings in detail, the numeral 1 designates a shaft which passes centrally through a rounded opening provided in a substantially U-shaped frame 2. The outer end of the shaft 1 is squared for the reception of the socket end of a removable handle 3. The inner end of the shaft 1 is reduced and threaded, as at 4 whereby the same may have screwed thereon cutter heads 5 or 6. The cutter heads are round in plan, the cutter head 5 having its active face concaved and provided with radial teeth which terminate a suitable distance away from its center. The cutter head 6 has its active face convex and provided with radial teeth which also terminate away from its center.

The opening in the frame 2, through which the shaft 1 passes, is of a materially greater area than the cross sectional diameter of the shaft, the said opening being threaded, and screwed through the said opening there is a follower member 7. The follower is in the nature of an exteriorly threaded tube, the bore of the said tube receiving therethrough the shaft 1, and providing a bearing for the said shaft. The outer end of the follower is provided with right angularly arranged projections forming the same with handles 8, whereby the follower may be screwed through the frame 100 to contact with the cutter head to force the same to its work.

The parallel arms of the inverted U-shaped frame 2 have their ends reduced, rounded and threaded. For distinction the 110 reduced ends are indicated by the numeral 9, the same passing through openings in the

straight ends 10 of one of the semi-circular members 11 of the clamp of the improvement. The shoulders between the parallel members of the frame and the ends thereof rest on the outer face of the clamp member 11, and nuts 12 are screwed on the said extensions 9 of the frame.

The second member of the clamp is of a construction similar to the member 11, and is indicated by the numeral 13. The member 13 has straight ends 14, and a semi-cylindrical body portion 15. In one of the ends 10 of the clamp member 11 there is pivotally secured a link 16 which is also received in a slot or opening in one of the straight ends 15 of the clamp member 13, a pivot 17 securing the link in the said end of the clamp member 13. In this manner the clamp members or sections 11 and 13 are hingedly connected, and also in this manner the clamp section 13 may be swung outwardly to a position approximately parallel with the clamp member or section 11. The opposite straight end of the clamp member 11 has pivoted therein a bolt member 18 which is designed to be swung through a slot or opening 19 in the second end 14 of the clamp member or section 13. The bolt 18 is engaged by a winged nut 20 which, when adjusted will hold the clamp sections assembled and the same in tight engagement with the collar or sleeve which is brazed or welded on the end of a pipe 21, or on the boss or nipple 22 which is integrally formed with the injector. The boss or nipple 22 is provided with exterior threads, and the outer end of the enlargement on the pipe 21 is formed with an outwardly projecting flange. The outer end of this flange is designed to be engaged by the teeth on the cutter head 5, as disclosed in Figures 1 and 2 of the drawing, while the outer end of the boss or nipple is faced by the cutter head 6.

The flange on the enlargement of the pipe 21 is designed to be contacted by the inner flanged end of the union which is screwed on the threaded boss or nipple to force the joints between the pipe and nipple to tight engagement.

The elements constituting my improvement may be readily separated to provide a small package for storage or shipment.

It is thought that the foregoing description, when taken in connection with the drawing will fully set forth the construction and operation of the improvement to those skilled in the art to which such inven-

tions relate. It is to be understood that my improved facing tool is comparatively small and is light in weight so that the same can be clamped on the boss or nipple of the injector without requiring the removal of the injector, and likewise the improvement may be readily clamped on the pipe to be connected to the injector. The manner in which the improvement is clamped on the boss or nipple or on the pipe effectively sustains the frame thereof in a position whereby the cutter heads will be positively arranged in proper position to operate on the pipe. The handle is turned by one hand of the operator, the other hand being employed for adjusting the follower 7. When the joint is faced, the follower is turned in a reverse direction which permits of the shaft and the cutter head carried thereby being moved away from the joint. The threads on the end 4 of the shaft are pitched in the direction of the turning of the handle 3, so that such turning, when the cutter head is in operative position will have the effect of screwing the said cutter head more tightly on the handle.

Having described the invention, I claim:—

1. A reamer comprising a pair of complementary clamp sections adapted to embrace one end of a tubular member to be reamed, means for locking the sections together on the tubular member, a U-shaped element having its ends passing transversely through the ends of one of the clamp sections, nuts threaded upon the ends of the U-shaped member, an adjusting member threaded through the crest of the U-shaped member and having a central bore, a shaft rotatable and slidable in the bore of the adjusting member, and a reamer element carried by the end of the shaft.

2. A reamer comprising a pair of hingedly connected clamp sections adapted to embrace one end of a tubular member to be reamed, means for locking the sections together on and about a tubular member, a U-shaped element fixed at its ends to and extending at right angles from the end portions of one of the clamp sections and having a central threaded aperture, a central tubular and exteriorly threaded member disposed in said aperture, a shaft rotatable and movable rectilinearly in said tubular member, and a reamer element carried at the inner end of the shaft.

In testimony whereof I affix my signature.

DAVID H. BROWDER.
